AMUSEMENT DEVICE

John Loeffler, Detroit, Mich.

Application May 2, 1939, Serial No. 271,321

3 Claims. (Cl. 272—27)

This invention relates to improvements in amusement devices, the principal object being to provide a device of this character which is apparently a puzzle but which in reality is a 5 deception and merely a toy adapted to afford considerable amusement to the owner at the expense of others.

Another object is the provision of an amusement device in the apparent form of a puzzle 10 having an innocent appearance and which upon being operated causes a pointed instrumentality to make contact with the hand of the operator.

A further object of the invention includes the provision of a device of the type described which 15 is extremely simple in construction, inexpensive to manufacture and one which will effectively carry out the purpose for which it is designed.

The above being among the objects of the present invention, the same consists in certain 20 novel features of construction and combinations of parts to be hereinafter described with reference to the accompanying drawing, and then claimed, having the above and other objects in view.

25 In the accompanying drawing which illustrates a suitable embodiment of the present invention and in which like numerals refer to like parts throughout the several different views,

Fig. 1 is a side elevational view of my amusement device illustrating the preferred method 30 of holding the same in the hand during operation thereof;

Fig. 2 is an enlarged transverse sectional view taken on the line 2—2 of Fig. 1;

35 Fig. 3 is a longitudinal sectional view taken axially through the device shown in the previous views as on the line 3—3 of Fig. 2, the device being shown in its inoperative position;

Fig. 4 is a view similar to Fig. 3 but illustrating 40 the device in its fully operated position;

Fig. 5 is an exploded perspective view of the component parts of the device with certain parts thereof shown in section and others in broken condition.

45 The amusement device comprising the present invention comprises what appears to be a solid stick of wood or other suitable material having a string or cord connected to the same. The block, however, is hollow and is interiorly provided with a needle or other like pointed instrumentality so constructed and arranged and connected to the string or cord that when the string or cord is pulled it will cause the point of the needle or other pointed instrumentality to project a short distance off from an end of the

block and in event the opposite ends of the block are held between the fingers of a person, will cause one of such fingers to be pricked with the needle. The needle is preferably of such small size and the opening into the end of the block 5 so correspondingly small that a cursory examination of the device by the ordinary person will fail to disclose it, thus aiding in carrying out the deception. Preferably in order to further 10 carry out the deception and to render it easier to catch an unsuspecting person with the trick, it is preferable to provide the free end of the string or cord with a loop or ring which may be slipped over the body of the device so as to 15 impart the appearance of a puzzle to it. The 20 deceptiveness of the device is preferably enhanced by winding an additional string or cord about the center portion of the body of the device so looped or knotted around the string or cord attached to the needle as to give it the 25 appearance of being an integral part of the first mentioned string or cord.

Referring now to the drawing it will be observed that the device includes a main body portion 10 which may be formed of any suitable 25 material but which for the purpose of economy and ease in manufacture will ordinarily be formed of wood. The main body 10 may be of any suitable cross-sectional configuration or of longitudinal contour so long as the shape or 30 contour adapts it to the purpose for which it is designed. It will ordinarily be found to be more economical to form it in the shape of a cylinder 35 as shown. As best brought out in Figs. 3, 4 and 5 the main body 10 is provided with a concentric bore 12 opening thereinto from one end and terminating short of the opposite end thereof. The open end of the bore 12 is closed by a plug 14 which preferably fits the walls of the bore 40 12 and is suitably secured in place as by gluing 45 or the like. The outer end of the plug 14 is preferably made flush with the corresponding end of the main body 10 and is preferably suitably finished off smoothly at its joint therewith and such joint, as well as the remaining surface 50 of the device, preferably covered with a suitable paint or the like so as to conceal such joint and to give the block the appearance of being solid.

The plug 14 is provided with a central bore 55 16 preferably of very small size as will herein- after be more fully explained. Within the chamber 18 formed in the main body 10 between the blind end of the bore 12 and the opposed end of the plug 14 is received a needle 20 or equivalent pointed instrumentality of greater length 55.

than the length of the chamber 18 and with its pointed end received in and guided by the bore 16 in the plug 14. The needle 20 is provided with an eye 22 at its inner end and while the needle 20 and eye 22 may be identical in all respects to conventional sewing needles found on the open market, it is preferable that the eye 22 be of greater width than ordinarily found in conventional sewing needles so as to facilitate the insertion of a string or cord therethrough. This may be accomplished by employing a conventional sewing needle and heating the eye portion thereof and inserting a pointed tool into the eye portion thereof to spread it to approximately the shape shown. A string or cord 24 has one end thereof passed through the eye 22 and tied in a knot so as to secure it thereto. A light coil spring 26 positioned in the chamber 18 surrounds the needle 20 and is maintained under longitudinal compression between the inner end the plug 14 and the knot of the string or cord 24 at the eye 22 of the needle 20. The spring 26 aids in centering the needle 20 in the chamber 18. It will be observed that the spring 26 constantly urges the needle 20 to the full extent of its movement within the chamber 18 in which position the point of the needle is withdrawn from view in the bore 16 of the plug 14 as illustrated in Fig. 3. The string or cord 24 extends within the chamber 18 from the eye 22, when the needle 20 is in normal inoperative position, towards the point of the needle to an opening 28 which extends through the wall of the main body portion 10 intermediate the length of the chamber 18. Thus it will be observed that by pulling on the string or cord 24 it will cause the needle 20 to be projected outwardly in the opening 16 against the force of the spring 26 as illustrated in Fig. 4, the extent of movement of the needle 20 in this respect being governed by the position of the opening 28 with respect to the eye 22 when in normal position and the position of the point of the needle with respect to the outer end of the plug 14 when the device is in inoperative position. Preferably the relation of the parts are such that when the string is pulled to project the needle 22 the full extent of its movement it will project from the corresponding end of the main body 10 and plug 14 a distance sufficient to give a person grasping such end a distinct prick but will not project a sufficient distance to cause any real injury to the operator. It might be noted that the amount of projection of the point of the needle as illustrated in Fig. 4 is exaggerated for the purpose of illustration only.

It will also be appreciated that in order to aid in carrying out the deception the diameter of the needle 20 should be relatively small, and the bore 16 and particularly the outer end portion thereof only of sufficient size to permit the needle to be projected the required distance therefrom. In other words the size of the bore 16 is preferably as small as practicable so as not to be readily apparent to one casually inspecting the device. It will also be appreciated that it is preferable to so proportion the various parts of the device that the hole 28 is positioned approximately midway between the ends of the main body 10 so that the cord 24 will appear to be centrally secured to the main body.

While the device thus far described is fully operative, the deceptive qualities of the same may be enhanced by concealing the fact that the string or cord 24 projects through an opening in the

main body 10. This is most conveniently taken care of by winding a second cord or string 30 about the main body 10 and providing one loop thereof on each side of the string or cord 24 and forming a loop in either one or both of the turns about the cord 24 as indicated at 32 in Fig. 1. By arranging the supplementary string or cord 30 in this manner and particularly where the loop 32 is provided about the string or cord 24, and by forming both strings or cords of the same material and of the same color it creates the impression that the string 24 is an integral part of the string 30 and the two parts are joined at the knot 32.

In order to render the device still more deceptive and to impart the appearance of a puzzle to the same so as to enable it to be worked upon an unsuspecting victim with greater ease, it is preferable to provide a loop on the end of the string or cord 24 permitting it to be extended over the main body 10. This may be either a loop formed in the string or cord 24 itself or may be a separate ring such as 34 tied to the free end of the string 24 as illustrated.

As a matter of illustration, with the device constructed as above described it may be represented to an intended victim as a puzzle in which the ring 34 is slipped over the main body 10 as illustrated in the drawing and the main body 10 grasped at the opposite ends thereof between the thumb and forefinger of a person as illustrated in Fig. 1 with the representation that the puzzle consists of getting the ring 34 off of the main body portion 10 without removing the thumb and forefinger from the opposite ends of the main body 10. The victim himself in attempting to get the ring 34 off the main body 10 according to instructions will usually inadvertently pull the string or cord 24 so as to cause the projection of the needle 20 sufficiently to prick his finger, or some other person knowing the trick may ostensibly manipulate the device while still held by the victim to demonstrate how the puzzle can be solved and thereby cause the projection of the needle 20 to the surprise and consternation of the victim.

It will, of course, be observed that after the string or cord 24 has been pulled to project the needle 20 the needle 20 will immediately be retracted as soon as the pull on the string or cord 24 is relieved, so that particularly where a needle of smaller diameter is employed and the opening for the same in the end of the plug 14 is exceedingly small, the victim quite often will fail to discover the reason for the effect produced until he is afforded a greater opportunity to study the construction and operation of the device or until it has been explained to him. In any event it has been found that the device is such as to produce considerable amusement among a group of persons.

Formal changes may be made in the specific embodiment of the invention described without departing from the spirit or substance of the invention, the scope of which is commensurate with the appended claims.

What I claim is:

1. In a device of the character described, in combination, a main body portion having a bore therein, a plug closing the open end of said bore whereby to form a chamber within said main body portion, said plug having a relatively small opening extending axially therethrough leading into said chamber, a needle-like device in said chamber having the pointed end thereof received in and guided by the walls of said opening and

normally fully concealed within said opening, a coil spring in said chamber surrounding said needle-like device, a flexible cord having one end thereof knotted through the eye of said needle-like device and extending through an opening in the wall of said main body portion intermediate the opposite ends of said needle-like device when in normal inoperative position, said coil spring being maintained under compression between the inner end of said needle-like device and the opposed end of said plug whereby to constantly urge said needle-like device toward retracted position, and the position of said opening in the wall of said main body portion through which said flexible cord extends being so related to the length of said needle-like device and the normal inoperative position of the point of said needle-like device in said opening in said plug as to limit the extent of projection of the point of said needle-like device 20 to a substantial but relatively short distance from the outer end of said plug when impelled thereby by a pull on said flexible cord.

2. In a device of the type described, in combination, a main body portion having the appearance of being solid but having a central chamber concealed therein and having a bore in one end thereof leading into said chamber, a needle-like device within said chamber having the pointed end thereof received in and guided for axial movement by said bore, spring means within said chamber constantly urging said needle-like device inwardly of said chamber whereby to conceal the point of said needle-like device in said bore, a flexible element secured to the innermost end of said needle-like device and projecting through a wall of said main body portion intermediate said innermost end and the point of said needle-like device whereby upon pulling said flexible element the point of said needle-like device will be caused to project through said bore and beyond the end 40 of said main body portion, and a ring on the end

of said flexible cord adapted to loosely encircle said main body portion.

3. In a device of the character described, in combination, a main body portion having a bore therein, a plug closing the open end of said bore whereby to form a chamber within said main body portion, said plug having a relatively small opening extending axially therethrough leading into said chamber, a needle-like device in said chamber having the pointed end thereof received in and guided by the walls of said opening and normally fully concealed within said opening, a coil spring in said chamber surrounding said needle-like device, a flexible cord having one end thereof knotted through the eye of said needle-like device and extending through an opening in the wall of said main body portion intermediate the opposite ends of said needle-like device when in normal inoperative position, said coil spring being maintained under compression between the inner end of said needle-like device and the opposed end of said plug whereby to constantly urge said needle-like device toward retracted position, the position of said opening in the wall of said main body portion through which said flexible cord extends being so related to the length of said needle-like device and the normal inoperative position of the point of said needle-like device in said opening in said plug as to limit the extent of projection of the point of said needle-like device to a substantial but relatively short distance from the outer end of said plug when impelled thereby by a pull on said flexible cord, and another flexible cord of the same character as the first mentioned flexible cord closely looped around said main body portion and around the first mentioned cord at the point of emergence thereof from said main body portion whereby to create the impression of forming an integral part of the first mentioned cord. 40

JOHN LOEFFLER.
